UNITED STATES PATENT OFFICE

94,439

DESIGN FOR A COMBINED ESCUTCHEON PLATE AND DOORLATCH FRONT

James B. Reynolds, Leominster, Mass., assignor
to Independent Lock Company, Fitchburg,
Mass., a corporation of Massachusetts

Application November 15, 1934, Serial No. 54,034

Term of patent 7 years

To all whom it may concern:

Be it known that I, James B. Reynolds, a citizen of the United States, residing at Leominster, in the county of Worcester and State of Massachusetts, have invented a new, original, and ornamental Design for a Combined Escutcheon Plate and Door Latch Front, of which the following is a specification, reference being had to the accompanying drawing forming part thereof.

Fig. 1 is a front view of a combined escutcheon plate and door latch front, and

Fig. 2 is an edge view thereof, showing my new design.

I claim:

The ornamental design for a combined escutcheon plate and door latch front as shown.

JAMES B. REYNOLDS.
